(57) **CLAIM**

The ornamental design for a equipment for control of electric power, as shown and described.

DESCRIPTION

FIG. 1.1 is a front view of an equipment for control of electric power;

FIG. 1.2 is a rear view thereof;

FIG. 1.3 is a left view thereof;

FIG. 1.4 is a right view thereof;

FIG. 1.5 is a top view thereof;

FIG. 1.6 is a bottom view thereof;

FIG. 1.7 is a first perspective view thereof;

FIG. 1.8 is a second perspective view thereof;

FIG. 1.9 is a view referencing a state of use and forms no part of the claimed design; and,

FIG. 1.10 is a view referencing a state of use and forms no part of the claimed design.

The broken lines showing for the purpose of illustrating the equipment for control of electric power form no part of the claimed design.
